The ornamental design for a resection guide, as shown and described.

DESCRIPTION

FIG. 1 is a front perspective view of the resection guide comprising the new design;

FIG. 2 is a back perspective view of the design of FIG. 1; FIG. 3 is a front elevational view of the design of FIG. 1; FIG. 4 is a back elevational view of the design of FIG. 1; FIG. 5 is a right side elevational view of the design of FIG. 1; where the left side elevational view is a mirror image thereof;

FIG. 6 is a top view of the design of FIG. 1; and,

FIG. 7 is a bottom view of the design of FIG. 1.

The broken lines in the figures are directed to the environment and are for illustrative purposes only; the broken lines form no part of the claimed invention.

The relatively light intermittently broken surface shading depicts contour, not surface decoration.
